United States Patent Office.

JAMES DOWD, OF BOSTON, MASSACHUSETTS.

Letters Patent No. 61,523, dated January 29, 1867.

IMPROVEMENT IN WAGONS.

The Schedule referred to in these Letters Patent and making part of the same.

TO ALL PERSONS TO WHOM THESE PRESENTS SHALL COME:

Be it known that I, JAMES DOWD, of Boston, in the county of Suffolk, and State of Massachusetts, have made a new and useful Improvement in Wagons, usually known under the name of "Jiggers;" and I do hereby declare the same to be fully described in the following specification and represented in the accompanying drawings, of which—

Figure 1 is a top view; and

Figure 2, a longitudinal section of one of my improved jiggers.

The common jigger in use has the front end of its platform suspended from a spring fixed on the front axle, in which case the platform extends underneath the axle. This prevents the front axle from being turned horizontally on its transom bolt farther than to bring one of its front wheels against the edge of the platform. In consequence of this a serious difficulty is often found in turning the wagon around in a narrow street or around a curve, but with my improvement the front axle may be revolved ninety degrees or more in either direction, whereby the turning of the vehicle in narrow places or about corners of streets will be greatly facilitated. In carrying out my invention, the platform of the jigger is not extended underneath the front axle but stops at a distance from the axis thereof equal at least to half the length of the axle, and besides this there extends from the front part of the platform a strong neck or arm, which rises vertically from the platform and afterward is bent or curved so as to extend horizontally over and above the front axle, and there is affixed to such arm, the upper part of what is termed the sweep.

In the drawings, A denotes the platform as applied in the ordinary way to the rear axle, a, which is what is termed a cranked axle. B is the neck or arm, which projects from the front end of the platform, the driver's seat b and foot-board c being affixed to such arm. In other words, the said seat may rest on springs, d, properly interposed between it and the arm. The front axle, shown at e, carries the wheels f f, the lower portion or frame, C, of the sweep being supported by springs resting on and fixed to the said axle. One of such springs is to be placed underneath each end of the frame C, as shown at D, in fig. 2. The upper portion, E, of the sweep is fixed to the arm B, the transom bolt being arranged as shown at F.

The above new mode of constructing the jigger renders it very convenient in use and capable of being moved or turned around with great facility. Another great advantage of the arm B is that it prevents a load, or any part thereof, from being thrown off the front end of the platform.

I claim the improved jigger, as made with the neck or arm B, combined and arranged with its platform A, the sweep-frames, their supporting springs, and front axle, the whole being substantially as described.

I also claim the application of the driver's seat, or the same and the foot-rest, to the arm or neck B, extending from the platform A, and over the front wheel, sweep-frames, and axle, as set forth.

JAMES DOWD.
